GUN SIGHT

Eli E. Gregory, Stirling, N. J.

Application January 23, 1939, Serial No. 252,429

11 Claims.

(Cl. 33—47)

This invention relates to gun sights, and in particular to certain new and useful improvements in a field-shooter's binocular gun sight.

The object of this invention is to increase the speed and accuracy with which a gun used in the field may be brought into a desired alignment, while permitting the shooter to use both eyes to find, follow, and gauge the distance to his target.

Prior sighting aids, for shotguns in particular, have been devised either after the pattern of rifle sights or on the principle of a narrow sighting rib. Neither of these methods is adapted to binocular use. The most common adaptation of the rifle sight to shotgun use is the ivory bead mounted singly or paired. When the shooter attempts to focus his two eyes on the target, and at the same time to align his weapon by means of such beads the phenomena of human binocular vision impose insuperable difficulties. He necessarily sees double all objects not in the plane on which his eyes are focused. The operation of the same phenomena transforms the narrow sighting rib, so effective when squinted over by one eye, into a pair of blurred lines. The purpose of this invention is to transform the handicap heretofore imposed by these phenomena upon binocular shooting into a positive advantage. The way in which I accomplish this result will become clear by reference to the accompanying drawings and from the following description:

Fig. 1 is a perspective drawing of a double-barreled shotgun equipped with my invention;

Fig. 2 is a cross-section of said double-barreled shotgun through the line 2—2 of Fig. 1;

Fig. 3 is a schematic diagram showing the operation of my invention;

Fig. 4 is an elevation of my invention embodied as a detachable sight adapted for attachment to an existing double-barreled shotgun;

Fig. 5 is a cross-section of the form of my invention shown in Fig. 4 through the line 5—5 of Fig. 4 and indicating the barrels of a double-barreled shotgun;

Fig. 6 is a plan view of a modified construction of my invention;

Fig. 7 is a plan view of a modified construction of my invention;

Fig. 8 is a plan view of a machine gun equipped with a modified construction of my invention;

Fig. 9 is a cross-section through Fig. 8 on the line 9—9;

Fig. 10 is a plan view of a machine gun equipped with a range-finding modification of my invention;

Fig. 11 is a cross-section through Fig. 10 on the line 11—11;

Fig. 12 is a cross-section through Fig. 10 on the line 12—12;

Fig. 13 shows a modified range-finding form of my invention; and

Fig. 14 is a longitudinal section through Fig. 13 on the line 13—13.

In Figs. 1 and 2 is shown a shotgun 1 having a rectangular sighting surface 2, substantially plane, integrally affixed to the barrels 3. Said surface 2 is substantially equal in length to said barrels 3, and is slightly greater in width than the average interpupillary distance of the human eyes. Its surface is preferably finished by some method whereby light reflection is reduced to a minimum.

Fig. 3, a schematic diagram, shows the eyes 4 of a shooter looking along the sighting surface 2 through the converging lines of vision 5 at a target 6. The actual rectangular sighting surface 2 is shown in solid lines in perspective and is slightly wider than the interpupillary distance of said eyes 4. The lines of vision 5 are shown as arrows. The two planes diagonally designated as A₁—B₁ and A₂—B₂, equal to said sighting plane 2 and indicated by dashed lines, represent the images of said sighting plane 2 visible to the right and left eyes of the shooter respectively, when his two eyes 4 are focused on the target 6, and show the apparent respective positions of these images.

The narrow plane diagonally designated A₁—B₁, and indicated by the hatched area, represents a narrow opaque sighting line in the center of the plane 2 which is visible to the shooter when his eyes 4 are focused on the target 6. This narrow plane A₁—B₁ is formed by the overlapping of the images seen by each eye separately, and is the only part of the actual sighting surface 2 appearing opaque to the shooter when his two eyes 4 are focused on the target 6, the balance of the images A₁—B₁ and A₂—B₂ seen by the right and left eyes respectively then appearing transparent. The width of this apparent narrow plane A₁—B₁ is just one-half the total amount by which the actual sighting plane 2 is wider than the interpupillary distance of the eyes 4.

The phenomena of binocular vision thus produce for the shooter a distinct narrow sighting line A₁—B₁ equal in length to sighting surface 2, and do so without conscious effort or eyestrain on the part of the shooter. In contradistinction to the effect of the ivory bead system of sighting, no distracting shift of focus from sight to target is necessary, and, in contradistinction to the effect of the narrow rib system, the visible effective sighting line is long and clear. The manifest advantage of a long sighting radius over a short one in reducing the effect of visual error is well recognized in the sighting art.

The foregoing explanation of the operation of my invention shows that it is not necessary that the sighting surface 2 be geometrically plane. On the contrary the controlling limitation on the geometry of this surface is that it be slightly wider than the interpupillary distance of the user, and the use of a substantially plane surface is prefer-

able merely as providing no distracting light reflections.

Figs. 4 and 5 show the sighting plane 2 embodied in a detachable unit with clips 7 adapted to attach it to particular existing weapons, for example, to the barrels 3 of a double-barreled shotgun.

Figs. 6 and 7 show a modified construction of my invention in which the sighting surface is slightly trapezoidal, not rectangular, in shape. In Fig. 6, the trapezoidal sighting surface 8 has its greater base 9 at the end nearer the eyes 4 of the user. The width of said greater base 9 may be made slightly wider than the greatest normal interpupillary distance of human eyes, and the width of the smaller base 10 may be made slightly wider than the smallest normal interpupillary distance of human eyes. In Fig. 7, the trapezoidal sighting surface 12 has its smaller base 10 at the end nearer the eyes 4 of the user. The width of said smaller base 10 may be made slightly wider than the smallest normal interpupillary distance of human eyes, and the width of the greater base 9 may be made slightly wider than the greatest normal interpupillary distance of human eyes. The difference in width between the width of the smaller base 10 and the wider base 9 thus constructed is on the order of 10-15 millimeters, this being the difference between the smallest and greatest normal interpupillary distance of human eyes. Thus, the taper resulting from the employment of this trapezoidal sighting surface is small and the sides thereof remain substantially parallel.

The effect of thus slightly tapering the sighting surface is to make a single surface adaptable to all normal people. When tapered as in Fig. 6, the apparent narrow sighting line 11 formed by the phenomena of binocular vision will appear tapered with its narrow end away from the user. When tapered as in Fig. 7, the apparent sighting line 13 will appear tapered with its wide end away from the user. The length of these apparent sighting lines will equal in each individual case that part of the length of the tapered sighting surface which is wider than the user's interpupillary distance. In those cases in which this length is less than the whole length of the tapered sighting surface, when said surface is tapered as in Fig. 6, the apparent sighting line 11 will appear to begin at the end of the surface near the user, when tapered as in Fig. 7, at the end away from the user. Thus the advantage of tapering as in Fig. 6 is to obtain an apparent sighting line 11 tapering toward the target; the advantage of tapering as in Fig. 7 is to obtain an apparent sighting line 13 giving a longer effective sighting radius.

The slightly trapezoidal sighting surface 8, shown in Fig. 6, may also be made so that its greater base 9 is slightly wider than the greatest effective interpupillary distance of the individual user, that is the interpupillary distance of an individual when his eyes are focused on a very distant object and its smaller base 10 substantially equals or is slightly less than the smallest effective interpupillary distance of the individual user, that is the interpupillary distance of the same individual when his eyes are focused on a near object, say 20 feet away. The difference between the width of the smaller base 10 and the greater base 9 thus constructed is small, and the sides of the sighting surface remain substantially parallel.

The effect of thus slightly tapering the sight-

ing surface is to make the length of the apparent narrow sighting line 11 vary in length with slightly changing interpupillary distance of the individual shooter. Since this interpupillary distance will vary with the distance to the target on which the shooter's eyes are focused, and since the sighting line 11 is only apparent when the surface 8 is wider than the effective interpupillary distance of the shooter, the length of the sighting line 11 becomes shorter as the distance to the target becomes greater. This results in automatic elevation of the muzzle in order to keep the apex of the sighting line 11 on the target, and is a great aid in overcoming the trajectory drop of shotgun pellets.

The modified forms of construction of my invention shown in Figs. 8-12 are particularly adapted to use on water-jacketed machine guns, but may be applied to any object to be aimed. The sighting surface 15 shown in Figs. 8-9 is 20 the outer cylindrical surface of a water jacket encasing the barrel 16 of the machine gun 14. This surface is so constructed that its effective width D is slightly greater than the interpupillary distance of the human eyes. It then operates 25 when the eyes of the user are focused on the target to form an opaque narrow sighting line as shown in the schematic diagram, Fig. 3.

The sighting surface 18 shown in Figs. 10-12 is the outer slightly conical surface of a water- 30 jacket encasing the barrel 16 of the machine gun 14. This surface is so constructed that its effective width at the far end d_1 is substantially equal to or slightly less than the smallest effective interpupillary distance of the individual user 35 and its effective width at the near end d_2 is slightly wider than the greatest effective interpupillary distance of the individual user. It then operates to form a narrow opaque tapered sight- 40 ing line whose apparent length varies with range 40 of the target on which the eyes of the user are focused in the manner hereinbefore described.

The modified range-finding construction of my invention shown in Figs. 13-14 is essentially a combination of an "opaque line" forming sight 45 19, of the type hereinbefore generally disclosed, and an "optical cross" forming sight 20, of the type disclosed in my Letters Patent No. 1,350,153. The "optical cross" forming sight 20, placed at far end of sight 19, is a tapered shape, the base 50 of which is slightly wider than the interpupillary distance of the human eyes. When the user of this range-finding modification of my invention looks along the "opaque line" forming sight 19 and focuses his eyes on the target, he sees 55 two images of the sight 20. These images appear transparent and in overlapping form an opaque central tapered image, the apex of which determines the point which should be aligned with the "opaque line" formed by the sight 19 60 and rested on the target. The farther away the target, the lower appears this apex, thus giving automatically corrected muzzle elevation for varying ranges.

The effective shape of the taper of sight 20 65 is operatively determined in the vertical plane, and is varied to accommodate the ballistic characteristics of the particular weapon with which it is employed. The angle α at which sight 19 meets sight 20 is determined by the effect of 70 sight 20 on the "opaque line" forming characteristics of sight 19. A relatively flat angle is more effective in producing the desired results of the combination than an abrupt one. Hence the taper of sight 20 must be relatively less than 75

when employed separately as an "optical cross" forming sight, in order to obtain an equally effective taper in the vertical plane.

The operation of this combination produces a greater range-finding effect than can be achieved with an "opaque line" forming sight alone, and at the same time produces a more positive alignment than can be achieved with an "optical cross" forming sight alone.

The operator of a machine gun employing my invention is naturally in the optimum position effectively to use the sight. The proper manner of using a shotgun equipped with my invention is for the shooter to place his eyes directly behind and slightly above the sighting surface. A slight offset of the stock may be found useful in comfortably attaining the correct position, but conventional guns may be used as well with a little practice.

While I have described my invention particularly in connection with shotguns of double-barreled construction and machine guns, it may be used in connection with any instrument to be aimed requiring quick and accurate alignment while the user thereof concentrates his visual effort on the point to be aligned with. In particular, my invention is readily adaptable to rifles, pistols, blowguns, and shotguns of all types. The particular structure disclosed, therefore, must be taken as an illustration and not as a limitation of my invention.

I claim:

1. As a binocular sight for an instrument to be aimed, an elongated sighting surface in fixed relation to said instrument having substantially straight apparent longitudinal boundary edges, a width slightly greater than the interpupillary distance of the human eyes and a length sufficient to be effective as a sight for said instrument.

2. As a binocular sight for an instrument to be aimed, an elongated sighting surface in fixed relation to said instrument having substantially straight apparent longitudinal boundary edges, a width at each end slightly greater than the interpupillary distance of the human eyes and a length sufficient to be effective as a sight for said instrument.

3. As a binocular sight for an instrument to be aimed, an elongated plane sighting surface in fixed relation to said instrument having substantially straight apparent longitudinal boundary edges, a width slightly greater than the interpupillary distance of the human eyes and a length sufficient to be effective as a sight for said instrument.

4. As a binocular sight for an instrument to be aimed, an elongated sighting surface in fixed relation to said instrument having substantially straight apparent longitudinal boundary edges, a width at the rear end slightly greater than the greatest normal interpupillary distance of human eyes, a width at the front end slightly greater than the smallest normal interpupillary distance of human eyes and a length sufficient to be effective as a sight for said instrument.

5. As a binocular sight for an instrument to be aimed, an elongated sighting surface in fixed relation to said instrument having substantially straight apparent longitudinal boundary edges, a width at the rear end slightly greater than the smallest normal interpupillary distance of

human eyes, a width at the front end slightly greater than the greatest normal interpupillary distance of human eyes and a length sufficient to be effective as a sight for said instrument.

6. As a binocular sight for an instrument to be aimed, an elongated sighting surface in fixed relation to said instrument having substantially straight apparent longitudinal boundary edges and a width at the rear end slightly greater than the greatest effective interpupillary distance of the individual user, a width at the front end substantially equal to the smallest effective interpupillary distance of the individual user and a length sufficient to be effective as a sight for said instrument.

7. As a binocular sight for an instrument to be aimed, an elongated substantially cylindrical sighting surface in fixed relation to said instrument having substantially straight apparent longitudinal boundary edges, a diameter slightly greater than the interpupillary distance of the human eyes and a length sufficient to be effective as a sight for said instrument.

8. As a binocular sight for an instrument to be aimed, an elongated slightly frusto-conical sighting surface in fixed relation to said instrument having substantially straight apparent longitudinal boundary edges, a diameter at the rear end slightly greater than the greatest normal interpupillary distance of human eyes, a diameter at the front end slightly greater than the smallest normal interpupillary distance of human eyes and a length sufficient to be effective as a sight for said instrument.

9. As a binocular sight for an instrument to be aimed, an elongated slightly frusto-conical sighting surface in fixed relation to said instrument having substantially straight apparent longitudinal boundary edges, a diameter at the rear end slightly greater than the greatest effective interpupillary distance of the individual user, a diameter at the front end substantially equal to the smallest effective interpupillary distance of the individual user and a length sufficient to be effective as a sight for said instrument.

10. In a binocular gun sight, the combination of an elongated substantially plane sighting surface having substantially straight apparent longitudinal boundary edges and a width slightly greater than the inter-pupillary distance of human eyes, and an "optical cross" forming device at the front end thereof, said device comprising a tapered member the base of which coincides with the front end of said elongated surface and the upper surface of which meets said elongated surface at an obtuse angle, the shape of the taper of said member determined by the shape of the taper of its projection parallel to the axis of said elongated surface according to the ballistic characteristics of the weapon on which it is employed which produces proper automatic elevation of that weapon by binocular optical effect.

11. In combination with a shot gun as a sight therefor and affixed horizontally on the upper surface of, parallel to, and coincident in length with the barrel or barrels thereof, a plane sighting surface having straight longitudinal boundary edges and a width slightly greater than the inter-pupillary distance of human eyes.
